(57) **CLAIM**

The ornamental design for a valve, as shown and described.

DESCRIPTION

Figure 1.1 is a perspective view of first embodiment of a valve tap showing my new design;

Figure 1.2 is a front elevation view thereof;

Figure 1.3 is a left elevation view thereof;

Figure 1.4 is a rear elevation view thereof;

Figure 1.5 is a right elevation view thereof;

Figure 1.6 is a top plan view thereof;

Figure 1.7 is bottom view thereof;

Figure 2.1 is a perspective view of second embodiment of a valve tap showing my new design;

Figure 2.2 is a front elevation view thereof;

Figure 2.3 is a left elevation view thereof;

Figure 2.4 is a rear elevation view thereof;

Figure 2.5 is a right elevation view thereof;

Figure 2.6 is a top plan view thereof; and

Figure 2.7 is bottom view thereof.

The broken lines shown in the figures are included for the purpose of illustrating portions of the valve tap and form no part of the claimed design.
